Donald J. Smith, Los Angeles, Calif.

Application April 16, 1945, Serial No. 119,045

Term of patent 3½ years

(Cl. D85—2)

To all whom it may concern:

Be it known that I, Donald J. Smith, a citizen of the United States, residing at Los Angeles, in the county of Los Angeles and State of California, have invented a new, original, and ornamental Design for a Combined Pipe Support and Match Pack Holder, of which the following is a specification, reference being had to the accompanying drawing, forming part thereof.

The figure is a perspective view of a combined pipe support and match pack holder embodying my new design.

I claim:

The ornamental design for a combined pipe support and match pack holder, substantially as shown.

DONALD J. SMITH.
